CLAIM

The ornamental design for a car seat cover for front seat, as shown and described.

DESCRIPTION

FIG. 1 is a front perspective view of a car seat cover for front seat showing my new design;

FIG. 2 is a front view thereof;

FIG. 3 is a rear view thereof;

FIG. 4 is a front perspective view showing the car seat cover of FIG. 1 installed on the front seat; and,

FIG. 5 is a rear perspective view showing the car seat cover of FIG. 1 installed on the front seat.

The broken lines shown represent unclaimed subject matter and form no part of the claimed design.

1 Claim, 5 Drawing Sheets(56)
